UNITED STATES PATENT OFFICE

140,550

DESIGN FOR A CENTRIFUGAL GOVERNOR

Raymond Reger, Anderson, Ind., assignor to The
Pierce Governor Company, Inc., Anderson, Ind.,
a corporation

Application December 11, 1944, Serial No. 116,829

Term of patent 14 years

(Cl. D55—1)

To all whom it may concern:

Be it known that I, Raymond Reger, a citizen of the United States and a resident of Anderson, county of Madison, and State of Indiana, have invented a new, original, and ornamental Design for a Centrifugal Governor, of which the following is a specification, reference being had to the accompanying drawing, forming part thereof.

Fig. 1 is a top plan view of a centrifugal governor showing my new design.

Fig. 2 is an end elevation taken from the left of Fig. 1 and

Fig. 3 is a similar view of the right end thereof. The dominant feature of my design resides in the portion disclosed in full lines.

I claim:

The ornamental design for a centrifugal governor, as shown and described.

RAYMOND REGER.
